FISHING LURE

Roy Phillips, 101 163rd Ave., Redington Beach, Fla.

Filed Jan. 22, 1959, Ser. No. 54,264

Term of patent 14 years

(Cl. D31—4)

FIG. 1

FIG. 2

FIG. 3

FIG. 4

Fig. 1 is a side elevational view of a fishing lure embodying my new design;

Fig. 2 is a top plan view thereof the bottom not shown being substantially like the top shown;

Fig. 3 is an end elevational view thereof taken from the left of Fig. 2; and

Fig. 4 is an end elevational view thereof taken from the right of Fig. 2.

I claim:

The ornamental design for a fishing lure, as shown and described.
